(57) **CLAIM**

We claim the ornamental design for an enclosure with roof dormer, as shown and described.

DESCRIPTION

FIG. 1 is an upper front perspective view showing our new design for an enclosure with roof dormer.

FIG. 2 is a lower front perspective view showing the design of FIG. 1.

FIG. 3 is a front elevation view showing the design of FIG. 1.

FIG. 4 is a rear elevation view showing the design of FIG. 1.

FIG. 5 is a right side elevation view showing the design of FIG. 1.

FIG. 6 is a left side elevation view showing the design of FIG. 1.

FIG. 7 is a top plan view showing the design of FIG. 1; and,

FIG. 8 is a bottom plan view showing the design of FIG. 1. In FIGS. 1-8, the broken lines are for purposes of illustration of environmental surface features and fixtures only, and do not form a part of the claimed design.

1 Claim, 8 Drawing Sheets
